(57) **CLAIM**

The ornamental design for a host connector, as shown and described.

DESCRIPTION

FIG. 1 is a top, front, and right side perspective view of a host connector showing our new design;

FIG. 2 is a top, front, and right side perspective view thereof, in use condition.

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken line in the drawing is included for the purpose of illustrating unclaimed environment and forms no part of the claimed design.
